US00D496595S1

(12) **United States Design Patent** (10) Patent No.: **US D496,595 S**
Raab et al. (45) Date of Patent: **** Sep. 28, 2004**

(54) **PORTABLE COORDINATE MEASUREMENT MACHINE PORTION**

(75) Inventors: **Simon Raab**, Maitland, FL (US); **Seyed Ali Sajedi**, Winter Park, FL (US); **Kenneth J. Hasloecher**, Deltona, FL (US); **Marc Barber**, Deltona, FL (US)

(73) Assignee: **Faro Technologies, Inc.**, Lake Mary, FL (US)

(**) Term: **14 Years**

(21) Appl. No.: **29/186,984**

(22) Filed: **Jul. 24, 2003**

Related U.S. Application Data

(63) Continuation-in-part of application No. 29/175,949, filed on Feb. 13, 2003, which is a continuation-in-part of application No. 29/166,332, filed on Aug. 26, 2002, now Pat. No. Des. 479,544, which is a continuation-in-part of application No. 29/155,790, filed on Feb. 14, 2002, now Pat. No. Des. 472,824.

CLAIM

The ornamental design for a portable coordinate measurement machine portion, as shown and described.

DESCRIPTION

FIG. 1 is a front perspective view of our new portable coordinate measurement machine portion including items in broken lines which are used herein and throughout the several Figures for illustrative purposes only and form no part of the claimed design;

FIG. 2 is a front view thereof;

FIG. 3 is a rear view thereof;

FIG. 4 is a side view thereof with the opposite side view being a mirror image thereof;

FIG. 5 is a top view thereof; and,

FIG. 6 is a bottom view thereof.
